PORTABLE DICTATING MACHINE

Monte L. Levin, New York, N.Y., assignor to
Roy M. Bloom, Scarsdale, N.Y.

Filed Nov. 28, 1967, Ser. No. 9,569

Term of patent 14 years

Int. Cl. D14—02

U.S. Cl. D26—14

FIGURE 1 is a top plan view of a portable dictating machine showing my new design;

FIGURE 2 is a side elevational view thereof;

FIGURE 3 is a further side elevational view thereof;

FIGURE 4 is a front elevational view thereof; and

FIGURE 5 is a rear elevational view thereof.

The dominant features of my design reside in the portions shown in full lines.

I claim:

The ornamental design for a portable dictating machine, as shown and described.
